UNITED STATES PATENT OFFICE.

JOHN R. SUNDEE, OF BUFFALO, NEW YORK, ASSIGNOR TO WARNER JEWELRY CASE COMPANY, OF BUFFALO, NEW YORK, A CORPORATION OF NEW YORK.

SPRING-LID JEWELRY-BOX.

1,161,166.

Specification of Letters Patent. Patented Nov. 23, 1915.

Application filed July 13, 1914. Serial No. 850,611.

To all whom it may concern:

Be it known that I, JOHN R. SUNDEE, a citizen of the United States, residing at Buffalo, in the county of Erie and State of New York, have invented new and useful Improvements in Spring-Lid Jewelry-Boxes, of which the following is a specification.

This invention relates to the class of boxes having a hinged lid and a spring which holds the lid either open or closed thus dispensing with a catch for retaining the lid in its closed position.

The object of my invention is to provide such boxes with an improved spring of this character which shall be simple and inexpensive in construction and which while having the necessary power to reliably close the lid, is easy and regular in action and presents no objectionable protuberance, thus rendering the improvement especially desirable for jewelry boxes.

In the accompanying drawings: Figure 1 is a perspective view of a jewelry box containing the invention. Fig. 2 is a vertical section thereof, showing the lid open. Fig. 3 is a similar section, showing the lid closed.

Similar characters of reference indicate corresponding parts in the several views.

1 indicates the body and 2 the hinged lid 30 of the box, which parts are both preferably stamped of sheet metal, although they may be constructed of any other suitable material.

Located within the box and seated on its bottom near its rear wall is a horizontal slide 3 which is movable toward and from said wall and arranged in suitable guides 4 secured to the bottom. This slide is constantly urged toward the lid-hinge by a suitable spring 5 preferably consisting of a wire bow-spring arranged crosswise of the slide and having its ends confined by lips or fastenings 6, while its intermediate portion bears against the front end of the slide.

45 The latter may be provided with a raised lip 7 under which the spring engages, as shown. The lips 6 are preferably struck up from the bottom of the sheet metal box, as shown.

Extending upwardly from the rear end of 50 the slide 3 and made rigid therewith is an

arm or standard 8 which bears against a cam or lug 9 rigidly secured to the interior of the rear wall of the lid and extending downwardly and forwardly below the lid in its closed position, as shown in Fig. 3. The 55 arm 8 is of sufficient height to remain in engagement with the cam in the open as well as the closed position of the lid, and in order to limit the opening movement of the lid, the arm terminates in a stop or lip 10 which is encountered by the cam, as shown in Fig. 2. To stiffen this arm and practically prevent its deflection relative to the slide, it is provided with a longitudinal reinforcing 60 rib or bead 11.

In the use of the box, the free end of the cam swings below the plane of the lid-hinge or dead center when the lid is closed and above the dead center when the lid is opened. On closing the lid, the cam pushes 70 the arm 8 and the slide 3 forward, straining the spring 5 until the cam passes below the dead center, when the spring by its reaction causes said arm to force the cam toward the rear wall of the box, thereby completing the 75 closing movement of the lid and yieldingly holding it shut. On opening the lid, the spring is strained until the cam passes above the dead center, when the reacting spring causes said arm to press the cam upwardly 80 until it strikes the stop 10 of the arm, thereby yieldingly holding the lid open.

The bow spring, being comparatively long, is smooth and regular in action and yet possesses the requisite power to fully 85 and reliably close the lid.

The slide and the spring are compact and occupy little space in the box, while the arm and the cam have so limited a movement that they produce no unsightly bulge of the 90 box-lining when the improvement is applied to a jewelry box, for which it is more particularly designed.

I claim as my invention:

The combination of the box, its hinged 95 lid, a slide mounted on the bottom of the box and movable toward and from the lid-hinge, said slide having at its rear end a rigid upright arm provided at its upper end with a stop, a bow-spring arranged in the 100

bottom of the box crosswise of said slide, said spring consisting of a piece of spring-wire having its ends confined and its intermediate portion engaged with said slide to 5 press the same rearwardly, and a cam carried by the rear portion of the lid and bearing against said arm.

Witness my hand this 3rd day of July, 1914.

JOHN R. SUNDEE.
